UNITED STATES PATENT OFFICE.

GILBERT F. QUINN, OF BEACHMONT, MASSACHUSETTS, ASSIGNOR TO SIMPLEX RUBBER COMPANY, OF BOSTON, MASSACHUSETTS.

RUBBER HEEL.

1,402,377.

Specification of Letters Patent. Patented Jan. 3, 1922.

Application filed March 6, 1919. Serial No. 230,956.

To all whom it may concern:

Be it known that I, GILBERT F. QUINN, a citizen of the United States, residing at Beachmont, in the county of Suffolk and 5 State of Massachusetts, have invented a new and useful Rubber Heel, of which the following is a specification.

The object of my invention is to provide a novel rubber heel of such shape that it 10 may be attached to the heel of the shoe by the repair man without requiring him to level or smooth off the leather base in order to provide a tight edge heel, thus saving much time for the repair man as well as 15 providing a more attractive heel.

In the accompanying drawings illustrating my invention—

Fig. 1 is a top plan view of my rubber heel;

20 Fig. 2 is a transverse section of same; and Figs. 3 and 4 are transverse sections of modified forms.

Like numerals designate like parts in the several views.

25 Referring to the accompanying drawings, I provide a rubber heel 1 which may have a chambered portion 2 as shown in Fig. 2, but which in my preferred and improved form has a central raised section 6 extending over 30 the central inner portion of the heel, the nails being driven through suitable nail holes 5, disposed substantially as indicated in the drawings. As illustrated in the drawings, the heel is narrower at the outer edges 35 than at its central portion. It has a generally cup-shaped inner portion which permits of its being readily attached to a leather heel having a rough surface, without requiring the repair man to work the surface 40 smooth, as is necessary when the conventional flat-surface rubber heels are used. It will also be observed that I provide a heel with a curved bottom surface, thereby effecting the greatest economy in the rubber 45 necessary to make the heel and securing a surface so shaped that the heel will not readily "skid" when it strikes the ground in walking.

All of the so-called "tight edge" rubber 50 heels now on the market to the best of my knowledge and belief are so constructed that the space on the attaching face of the rubber heel that lies between the outer edge and the nail hole becomes a perfectly flat plane 55 when the nails are driven home in attach-

ing the rubber heel to a shoe, whereas my construction provides a bridge element which spans over the space between the point where the nail enters the shoe and the extreme outside edge of the heel which 60 effects a better tight edge than heels of any other construction, by virtue of the fact that the entire pressure caused by the downward movement of the entire rubber heel structure is at all times centered on the extreme out- 65 side edge of the heel and such pressure cannot be interrupted or arrested by the roughness of the leather base to which the rubber heel is attached.

An important saving in the quantity of 70 rubber required for making the heel is accomplished by the construction illustrated, and the portions 3 provide the necessary means to support the heel in the designed position relative to the shoe, and obviate the 75 necessity of the shoemaker smoothing the bottom of the heel before attaching the rubber heel. An important practical advantage is thus obtained as it makes it unnecessary for the repair man to level or smooth off the 80 leather base in the slightest which he must do before applying other tight edge heels, thus saving much time for the repair man and insuring the action of all the pressure of the entire rubber heel edge against the 85 extreme outside edge of the leather base to which it is attached, which obviates the necessity of using any cement whatsoever by the repair man, which also is a great saving.

What I claim is:

1. A rubber heel having a cupped upper surface, and having a correspondingly rounded bottom surface, the upper surface having a raised section extending over the central portion of the heel, the heel being 95 thicker in said section than at the marginal portion, said section being of sufficient size to include the portion of the heel in which the nail holes are positioned and the bottom of the heel presenting a rounded surface 100 after it is attached to the shoe.

2. A cushion heel comprising a body having a raised central portion flat upon its top face and having the outer portions of the heel inclined upwardly, the heel being 105 thickest over its central portion, and having a generally curved bottom surface, whereby the heel may be readily attached to the rough surface of a leather shoe heel.

3. A rubber heel having a concave central 110

portion, and having a raised section in said central portion positioned a substantially uniform distance from the outer edge of the heel and of suitable size to receive nails, the 5 heel having a channel encircling the raised section to permit of the heel being tightly secured to the shoe along its edge, the marginal portions of the heel being inclined up-

wardly and the bottom surface of the heel presenting an upward slanting wearing surface at the rear portion of the heel after 10 the heel has been attached to the shoe, the bottom surface of the heel being of approximately arcuate shape when applied to the shoe heel.

GILBERT F. QUINN.
